Geo. P. Kimmel.
ATTORNEY.

UNITED STATES PATENT OFFICE.

ARVI ALTO, OF WAREHAM, MASSACHUSETTS.

ATTACHMENT FOR SEWING MACHINES.

Application filed March 10, 1924. Serial No. 698,239.

To all whom it may concern:

Be it known that I, ARVI ALTO, a citizen of Finland, residing at Wareham, in the county of Plymouth and State of Massachusetts, have invented certain new and useful Improvements in Attachments for Sewing Machines, of which the following is a specification.

This invention relates to an attachment for sewing machines and is designed primarily for use in the manufacture of moccasins, but it is to be understood that an attachment in accordance with this invention can be employed for any purpose for which it is found applicable, and the invention has for its object to provide, in a manner as hereinafter set forth, an attachment for sewing machines including means to expedite the sewing of the sections of a moccasin together, that is to say, the top or the upper to the bottom or body portion of the moccasin.

Further objects of the invention are to provide, in a manner as hereinafter set forth, an attachment for sewing machines for the purpose referred to and which is simple in its construction and arrangement, strong, durable, thoroughly efficient and convenient in its use, readily assembled, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a top plan view of an attachment in accordance with this invention, showing the adaptation thereof in connection with the sections of a moccasin.

Figure 2 is a longitudinal sectional view of a moccasin showing the adaptation thereof with of an attachment in accordance with this invention.

Figure 3 is a side elevation of the attachment and further illustrating the moccasin in dotted lines.

An attachment in accordance with this invention provides means for holding the sec-

tions of a moccasin together, with the opposed marginal portions of the sections extended in position to be sewed or stitched, and further to constitute a guide during the sewing or stitching operation and to present the extended opposed marginal portions of the sections of the moccasin in the path of the needle of the sewing machine.

Referring to the drawings in detail, 1 denotes the top section or upper of the moccasin and 2 the bottom or body section thereof and when said sections are in position to be stitched or sewed together, they are maintained in abutting relation and with the opposed marginal portions thereof extended and clamped together in the manner as shown in Figures 2 and 3. The extended marginal portion of the section 1 is indicated at 3, and that of the section 2, at 4. When the sections 1 and 2 are arranged to be sewed or stitched, the marginal portion of the lower part of section 1 is extended a sufficient distance and the marginal portion of the top of the section 2 is also extended a sufficient distance so that the extended marginal portions will be of the necessary width to receive the stitching so that the said sections will be properly secured together to complete the moccasin.

The sections of the moccasin are mounted upon a sectional last 5 of the desired contour for the purpose of affording the desired shape to the moccasin and the sections of the latter when mounted on the last 5 are clamped thereto by the attachment forming the subject matter of this invention.

The attachment includes a pair of oppositely disposed combined track and holding elements and each of which is resilient for the purpose of clamping the sections of the moccasin to the last 5. One of said elements is indicated at 6 and the other at 7, and each of which is constructed of any suitable material, preferably spring metal. The element 6 is extended around the upper portion of the last 5 and further is positioned on the top, at the forward end, of the last 5. The element 7 is extended around the last 5 and is arranged below as well as being spaced from the element 6. The sections 1 and 2 of the moccasin are interposed between the elements 6 and 7 and the last 5 whereby the sections of the moccasin are clamped in position. When the elements 6 and 7 are set up to secure the sections 1 and 2 to the last 5, the marginal portions 3, 4 of the sections 1, 2,

project outwardly between the opposed edges of the elements 6, 7.

The element 6 is offset throughout to provide a track 8 and a guide groove 9, and the element 7 is offset to form a track 10 and a guide groove 11.

The element 6, at its forward portion, between the side portions and the forward portion of the track 8, is flat and forms what

10 may be termed a semi-oval shaped holder member 19, adapted to be positioned against the forward part of the section 1 of the moccasin for holding it down during the stitching of the section 1 to the section 2 of the moccasin. That part of the element 6, indicated at 19', which extends rearwardly from the member 19 and projects inwardly and upwardly from the side portions and rear portion of the track 8, forms what may 15 20 be termed a positioning member for said element 6, as the said part 19' surrounds the rear or high part of the sectional last. See Figures 1 and 2.

Formed integral with the forward part 25 of the holder member 19' is a rearwardly extended centrally disposed locking lug 12, with which associates a resilient locking bar 13 formed at its rear end with a depending lug 14, which seats on the last 5. The locking bar 13 has extending therethrough a threaded rod 15, carried by the last 5 and mounted on the rod 15 is an adjusting nut 16 which bears against the bar 13.

When the sections of the moccasin are 35 mounted on the last 5, the bar 13 is sprung under the lug 12 which retains the forward portion of the section 1 of the moccasin upon the forward portion of the last 5. The rear portion of the section 1 of the moccasin 40 is retained against the last by the element 6.

Cooperating with the element 6 is a guide member 17, which is connected to the sewing machine (not shown) and said guide member 17 at its lower end has a groove 18 into 45 which extends the track 8, whereby the element 6 is connected to the member 17, and during the shifting of the last 5 with the sections of the moccasin thereon, the element 6 is guided and retained in position by the member 17. The elements 6 and 7 provide 50 means to retain the extended marginal portions 3, 4, in position to be acted upon by the needle of the sewing machine.

Cooperating with the element 7 is a combined guide and holder member 20 having a grooved guide at its lower end, as at 21, for the reception of track 10, whereby the member 20 will be connected to the element 7 during the operation of stitching the moccasin. The member 20 has an opening 22 60 for the passage of the needle.

The members 17 and 20 act as a means to properly guide the moccasin when it is shifted for the purpose of securing the extended marginal portions 3, 4, together.

After the extended marginal portions 3, 4 have been secured together throughout, the nut 16 is adjusted upwardly on the rod 15, which releases the bar 13 and the element 6 can then be pulled off section 1. After the removal of element 6, the element 7 is pulled off section 2 and the last 5 is then removed from the moccasin.

What I claim is:—

1. An attachment for sewing machines 75 for the purpose set forth comprising a pair of oppositely disposed continuous combined track and holding elements for clamping the sections of a moccasin to a last and further for maintaining the opposed marginal portions of said sections extended to be stitched, one of said elements having a holder member at its forward portion and a positioning member at its rear portion, and a pair of guide members, each of said guide members 80 having one of said elements slidably connected therewith.

2. An attachment for sewing machines for the purpose set forth comprising a pair of oppositely disposed continuous combined 90 track and holding elements for clamping the sections of a moccasin to a last and further for maintaining the opposed marginal portions of said sections extended to be stitched, a pair of guide members, each of 95 said guide members having one of said elements slidably connected therewith, and a resilient locking bar coacting with one of said elements.

3. An attachment for sewing machines 100 for the purpose set forth comprising a pair of oppositely disposed continuous combined track and holding elements for clamping the sections of a moccasin to a last and further for maintaining the opposed marginal portions of said sections extended to be stitched, one of said elements having a holder member at its forward portion and a positioning member at its rear portion, a pair of guide members, each of said guide members having one of said elements slidably connected 105 therewith, and a resilient locking bar co-acting with said holder member.

4. An attachment for sewing machines for the purpose set forth comprising a pair 115 of continuous combined holding and track elements adapted to clamp the sections of a moccasin to a last and with the opposed marginal portions of the sections extending between and projecting outwardly from said elements, each of said elements offset to provide the track, said elements arranged in superposed relation and one having a holder member at its forward portion and a positioning member at its rear portion, and a pair of guide members, each of said guide members 120 slidably connected to one of said tracks.

5. An attachment for sewing machines for the purpose set forth comprising a pair 130

of continuous combined holding and track elements adapted to clamp the sections of a moccasin to a last and with the opposed marginal portions of the sections extending between and projecting outwardly from said elements, each of said elements off set to provide the track extending throughout thereof, one of said elements having a holder member at its forward portion and a posi-

tioning member at its rear portion, said 10 holder member formed with a lug, a pair of guide members, each of said guide members slidably connected to one of said tracks, and a locking device co-acting with said lug.

In testimony whereof, I affix my signature hereto.

ARVI ALTO.
